US00D912045S

(12) **United States Design Patent** (10) **Patent No.:** **US D912,045 S**
(45) **Date of Patent:** **** Mar. 2, 2021**

(54) **ELECTRONIC DEVICE**

- (71) Applicant: **SAMSUNG ELECTRONICS CO., LTD.**, Suwon-si (KR)
- (72) Inventors: **Dhojin Han**, Suwon-si (KR); **Donghun Kim**, Suwon-si (KR); **Yangjic Lee**, Suwon-si (KR)
- (73) Assignee: **SAMSUNG ELECTRONICS CO., LTD.**, Gyeonggi-do (KR)
- (**) Term: **15 Years**

(21) Appl. No.: **29/694,312**

(22) Filed: **Jun. 10, 2019**

(30) **Foreign Application Priority Data**

- Dec. 19, 2018 (KR) 30-2018-0060150
- (51) **LOC (13) Cl.** **14-03**
- (52) **U.S. Cl.**
USPC ..... **D14/341**; D14/138 AD
- (58) **Field of Classification Search**
USPC ..... D14/341, 388-389, 374, 345, 371, 426, D14/129, 130, 138 R, 138 AA, 138 C, D14/138 G; D21/324, 329, 330
CPC G06F 1/1652; G06F 1/1616; G06F 1/1624; G06F 1/1643; G06F 1/1647; H04M 1/0268; H04M 1/0235; G09F 9/301

CLAIM

The ornamental design for an electronic device, as shown and described.

DESCRIPTION

FIG. 1 is a front perspective view of an electronic device showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is another front perspective view of the electronic device in an alternate position in which the showing an extended state of the electronic device in which the display screen is extended to the right side;
FIG. 9 is a front view of FIG. 8;
FIG. 10 is a rear view of FIG. 8;
FIG. 11 is a left-side view of FIG. 8;
FIG. 12 is a right-side view of FIG. 8;
FIG. 13 is a top view of FIG. 8; and,
FIG. 14 is a bottom view of FIG. 8.

The broken lines illustrating portions of the electronic device form no part of the claimed design.

1 Claim, 10 Drawing Sheets
